RAILWAY TRAFFIC CONTROLLING
APPARATUS

Ralph K. Crooks, Sharpsburg, Pa., assignor to
The Union Switch & Signal Company, Swiss-
vale, Pa., a corporation of Pennsylvania

Application November 16, 1940, Serial No. 365,886

10 Claims. (Cl. 246—63)

My invention relates to railway traffic controlling apparatus and more particularly to train carried train control apparatus responsive to coded current.

Railway traffic controlling apparatus responsive to coded energy is well known and train carried train control apparatus responsive to coded alternating track circuit current has found wide use. The track circuit customarily includes the track rails of a track section and the alternating current supplied thereto is coded by being periodically interrupted at a preselected rate. The alternating current is ordinarily of 100 cycles per second. Such coded alternating current has alternate on and off periods, current flowing during each on period and no current flowing during each off period. The on and off periods of a code are ordinarily of equal durations. Such track circuit current is coded at any one of several different code rates according to different traffic conditions, the code rates of 180, 120 and 75 interruptions per minute being those commonly used to reflect clear, approach-medium and approach traffic conditions, respectively.

A receiving circuit is mounted on the train in inductive relation to the track rails to receive an electromotive force in response to each on period of the track circuit current. The electromotive force thus picked up by the receiving circuit has the same frequency as that of the alternating current supplied to the track rails and is of the same code rate as the rail current. The electromotive force picked up by the train carried receiving circuit is amplified by means of an electron tube amplifier and is used to control the operation of a code following relay, such relay being operated at a rate corresponding to the code rate of the rail current. The code following relay is coupled to the plate circuit of the amplifier tube and is operated in response to the variations of the plate circuit current as caused by the voltage applied to the control grid of the tube during the on and off periods of the electromotive force received from the track rails. That is to say, the code following relay is operated in response to the variations of the plate current caused by the variations of the voltage applied to the grid during the on and off periods of the code.

The code following relay in turn selectively governs cab signal and train brake control equipment through the medium of a decoding means which is selectively responsive to the several different code rates. The decoding means usually includes different tuned circuits, each such cir-

cuit being tuned for response to current of a frequency corresponding to a respective code rate of the track rail current. The code following relay controls the supply of current to the decoding means in such a manner that current of a frequency corresponding to the rate at which the relay is operated is supplied to the decoding means.

In such systems heretofore proposed, an intermittent open circuit condition of one of the amplifier circuits may cause operation of the code following relay, and if such open circuit condition is of a rate corresponding to a code rate used for the track rail current false control of the decoding means may occur which in turn may create a false signal aspect.

It is customary to provide on railway trains a 32 volt source of current, such as a battery or direct current generator for supplying current to train lighting circuits, locomotive headlight circuits, and similar equipment. It is desirable that the same train carried source of current be used as the current source for the train control apparatus without the necessity of providing means such as a dynamotor or a motor generator to convert the 32 volts of the usual source of supply to some other voltage.

In view of the foregoing conditions, a feature of my invention is the provision of a novel and improved low voltage electron tube amplifier for railway traffic controlling apparatus.

Another feature of my invention is the provision in railway traffic controlling apparatus of a novel and improved amplifier operable from a single 32 volt source of direct current.

Again, a feature of my invention is the provision of an improved amplifier for railway traffic controlling apparatus wherein a relatively large ratio of change in the plate circuit current of a vacuum tube to a change in the applied alternating grid voltage is effected.

Still another feature of my invention is the provision in railway traffic controlling apparatus of novel and improved means wherewith false operation of a signal or brake control device from intermittent open circuit conditions is avoided.

To obtain the above features, as well as other advantages of my invention which will become apparent as the specification progresses, I provide according to my invention a low voltage type of electron tube with heater and plate circuits, each of which circuits is operable when connected to a 32 volt source of direct current. The grid circuit of such electron tube is coupled to the train carried receiving circuit to apply an

alternating grid voltage to the tube in response to coded alternating rail current, such grid voltage being effective to control the plate circuit current. The alternating current component of the plate circuit current is used to control a slow release relay and hence such slow release relay checks the presence of the coded alternating current. The change effected in the average value of the direct current component of the plate circuit current is used to control a code following relay in the usual manner. To increase the ratio of the change in plate circuit current to a given change in applied alternating grid voltage, a special plate circuit of relatively high impedance to both the alternating current component and the low frequency variations of the plate circuit current is provided. To this end a winding is interposed in the plate circuit and which winding is by-passed by a condenser effective to by-pass the alternating current component but not the low frequency variations of the plate circuit current. This winding may be the operating winding of a code following relay or it may be the primary winding of a low frequency type of transformer to the secondary winding of which the code following relay is connected. Hence the code following relay is operated by the energy supplied thereto due to the low frequency variations of the plate circuit current. A reactor transformer is also furnished and a primary winding of this latter transformer is interposed in the plate circuit in series with the condenser. This reactor transformer furnishes a high impedance to the alternating current component of the plate circuit current. A slow release relay is connected to a secondary winding of the reactor transformer and is effectively energized and picked up in response to the alternating current component of the plate circuit current. These two transformers provide a plate circuit of high impedance and that effects a substantially large ratio of change in the plate circuit current to a given change in the applied grid voltage.

The supply of current to the decoding means is controlled over a front contact of the slow release relay and contacts of the code following relay and hence an intermittent open circuit condition of any one of the amplifier circuits while it might cause operation of the code following relay, will not cause energization of the slow release relay with the result that the decoding means is not operated falsely to create a false signal aspect due to an intermittent open circuit condition.

I shall describe two forms of apparatus embodying my invention, and shall then point out the novel features thereof in claims.

In the accompanying drawings, Fig. 1 is a diagrammatic view showing one form of apparatus embodying my invention when used with train carried train control apparatus. Fig. 2 is a diagrammatic view showing another form of apparatus embodying my invention when used with train carried train control apparatus. Fig. 3 is a diagram illustrating operating characteristics of the apparatus of Figs. 1 and 2.

In each of the different views, like reference characters are used to designate similar parts.

Referring to Fig. 1, the reference characters 1a and 1b designate the track rails of a railway. These rails 1a and 1b would be formed by the usual insulated rail joints, not shown, into consecutive track sections, and the rails of each section would be supplied with coded alternating

current, the alternating current being of a frequency of say, for example, 100 cycles per second. The trackway apparatus for supplying coded current to the rails is not shown since it forms no part of my invention and may be any one of several well-known arrangements. The arrangement of such trackway apparatus may be that disclosed in Letters Patent of the United States, No. 1,986,679, granted January 1, 1935, to L. V. Lewis for Railway traffic controlling apparatus, and it is sufficient for the instant application to point out that the track rails 1a and 1b are supplied with alternating current coded at the rate of 180, 120 and 75 cycles per minute in response to clear, approach-medium and approach traffic conditions, respectively.

Two inductors 2 and 3 are mounted on a train in inductive relation to the track rails 1a and 1b, respectively. Inductors 2 and 3 are connected into a receiving circuit which also includes a condenser 4 and the primary winding 5 of a transformer T1. A condenser 6 is connected across a secondary winding 7 of transformer T1 and the transformer and receiving circuit are tuned to resonance at the frequency of the rail current. That is, when alternating current of 100 cycles is used then the train carried receiving circuit and transformer T1 are tuned to resonance at the frequency of 100 cycles per second.

It is to be understood, of course, that my invention is not limited to the use of 100 cycle alternating current, but alternating current of such frequency is widely used and is used here for the purpose of illustration, but the alternating current can be of any convenient frequency.

It follows that an alternating electromotive force appears across the terminals of secondary winding 7 and condenser 6 in response to the coded alternating current supplied to the track rails, such electromotive force being of the same frequency and code rate as that of the current supplied to the track rails.

A low voltage electron tube TT is carried on the train. Electron tube TT may be of any one of several types and as here shown it is a tetrode, having a plate 8, a cathode 9, a control grid 10, another grid 11 and a filament 12.

The reference TB designates a 32 volt source of direct current, such as a battery. Preferably the current source TB would be that usually provided on the railway train for supplying current to the train lighting circuits and similar equipment, but it is to be understood that my invention is not limited to the use of the usual train carried current source and the current source TB may be independent and used only for the train control equipment. Furthermore, it is to be understood that my invention is not limited to a 32 volt source of current and a low voltage source of a voltage other than 32 volts may be used.

A heater circuit is provided for electron tube TT by connecting the filament 12 across the battery TB as will be understood by an inspection of Fig. 1. Preferably cathode 9 is connected to the negative terminal of filament 12 and grid 11 is connected to the positive terminal of filament 12. A grid circuit for tube TT extends from control grid 10 over blocking condenser 15 and a resistor 16 in multiple, secondary winding 7 of transformer T1 and condenser 6 in multiple and thence to cathode 9. Tube TT is provided with a plate circuit which can be traced from the positive terminal B32 of battery TB over primary winding 13 of a reactor transformer T2, to be later

referred to, primary winding 14 of a low frequency transformer T3, to be also referred to later, plate 8 and intervening tube space to cathode 9 of tube TT and thence to the negative terminal C32 of battery TB. A condenser 17 is connected across primary winding 14 of transformer T3. A polar code following relay MS is connected to secondary winding 18 of transformer T3 through a full wave rectifier 19, and a slow release relay RS is connected to secondary winding 20 of transformer T2 through a full wave rectifier 21.

Code following relay MS is preferably a polar relay whose contact member 25 is biased to normally engage a normal contact 26 and is operated to engage a reverse contact 27 when the relay is energized by current of a preselected polarity. Relay RS is a neutral slow releasing relay. Relays MS and RS control the supply of current to the primary winding 22 of a decoding transformer DT, the secondary winding 23 of which is connected to the input terminals of a decoding means DM. When relay RS is picked up closing front contact 24 and relay MS is de-energized and its contact member 25 engages normal contact 26, direct current from battery TB is supplied to the left-hand portion of primary winding 22 of transformer DT, and when relay MS is energized at a preselected polarity to operate its contact member 25 to engage reverse contact 27 and relay RS is also picked up, current flows from battery TB to the right-hand portion of primary winding 22. Thus with relay RS picked up and relay MS operated direct current is alternately supplied to the two portions of primary winding 22 of transformer DT and there is induced in secondary winding 23 of that transformer an alternating electromotive force of a frequency corresponding to the rate at which relay MS is operated. The electromotive force thus induced in secondary winding 23 is applied to the decoding means DM.

The decoding means DM may be any one of the several well-known forms and may be the tuned circuit arrangement covered by Letters Patent of the United States No. 1,773,515, granted August 19, 1930, to C. C. Buchanan for Railway traffic controlling apparatus. It is sufficient for this application to point out that three control relays A, R and L connected to the output side of decoding means DM are selectively controlled according to the frequency of the current supplied to its input terminals. As here shown, relays A and L are effectively energized and picked up when decoding means DM is supplied with current of a frequency created by operation of relay MS at a rate corresponding to the 180 code rate of the track rail current. Relays R and L are effectively energized and picked up and relay A is released when current of a frequency created by operation of relay MS at a rate corresponding to the 120 code rate of the rail current is supplied to the decoding means DM, and relay L is effectively energized and picked up and relays A and R are released when the decoding means DM is supplied with current of a frequency corresponding to operation of relay MS in response to track rail current of the 75 code rate. All three of the control relays A, R and L are released when code following relay MS is inactive and when relay RS is released.

Control relays A, R and L are used to control the operating circuits of train control apparatus here shown as a cab signal CS, signal CS being a four-position color light signal. The operating

circuits for signal CS are those commonly employed and as here shown when relay A is picked up closing front contact 28 an operating circuit easily traced is formed for lamp 29 and that lamp is illuminated to cause signal CS to display a clear signal indication. When relay A is released, closing back contact 30 and relay R is picked up closing front contact 31, an operating circuit is formed for lamp 32 and that lamp is illuminated to cause signal CS to display an approach-medium signal indication. When relays A and R are released, closing back contacts 30 and 33, respectively, and relay L is picked up closing front contact 34, an operating circuit is formed for lamp 35 and that lamp is illuminated to cause signal CS to display an approach signal indication. When relays A, R and L are released closing back contacts 30, 33 and 36, respectively, an operating circuit is formed for lamp 37 and that lamp is illuminated to cause signal CS to display a slow speed signal indication.

In describing the operation of the apparatus of Fig. 1, reference is also made to the plate-current plate-voltage characteristic curves of Fig. 3. With filament 12 of tube TT heated and with no electromotive force picked up by the receiving circuit so that the potential of grid 10 with respect to the cathode 9 is zero (e. g.=0) and the 32 volts from battery TB are impressed on the plate circuit a given steady direct current flows in the plate circuit. This condition is indicated by the curve C1 of Fig. 3, the value of the plate voltage being indicated by line PV of Fig. 3 and the value of the plate current being indicated by line PA. Under this condition of steady direct current in the plate circuit, no energy is transferred through either transformer T2 or T3, and relay RS is released and code following relay MS is inactive. This condition of relays RS and MS causes no electromotive force to be induced in secondary winding 23 of the decoding transformer DT and hence the control relays A, R and L are all deenergized and released with the result that lamp 37 is illuminated to cause signal CS to display a slow speed signal indication. It follows that absence of track rail current causes a slow speed cab signal indication.

I shall next assume that alternating current of the 75 code rate is supplied to the rails 1a and 1b and a corresponding alternating electromotive force is picked up by the receiving circuit. This alternating electromotive force is applied between the control grid 10 and cathode 9 of tube TT. The blocking condenser 15 and resistor 16 function in the usual manner and hence the potential of control grid 10 is varied with respect to cathode 9 during the on period of the code by each cycle of the rail current. Such electromotive force picked up by the receiving circuit has a frequency of 100 cycles per second and an alternating current component of corresponding frequency is created in the plate circuit current. Furthermore, due to the effect of blocking condenser 15 and resistor 16, the average value of the direct current component of the plate circuit current is decreased during each on period of the code and is then restored to its normal value during each off period. The condenser 17 is effective to by-pass the alternating component of the plate circuit current around primary winding 14 of transformer T3 but is not effective to bypass the variations of the direct current component of the plate circuit current. Hence each time the average value of the direct current plate circuit current is decreased at the start of an on

code period and is increased at the start of each off period of the code an electromotive force is induced in secondary winding 18 of transformer T3. This electromotive force induced in secondary winding 18 is rectified and unidirectional current is supplied to relay MS which energizes that relay at the previously mentioned preselected polarity causing contact member 25 of the relay to be operated to engage reverse contact 21, contact member 25 being operated back to engage normal contact 26 subsequent to each operation to the reverse position by the biasing means of the relay. The alternating current component of the plate circuit current induces an electromotive force in secondary winding 20 of transformer T2 which electromotive force is rectified and unidirectional current is supplied to relay RS and that relay is energized and picked up. Current is supplied to relay RS only during the on period of the code, but relay RS is maintained picked up during each off period of the code, due to its slow release characteristics. It follows that relay RS is picked up and code following relay MS is operated at a rate corresponding to the 75 code rate of the track rail current which rate of operation of relay RS is effective to cause relay L to be picked up and relays A and R to be released with the result that lamp 35 is illuminated to display an approach signal indication.

When the rail current is coded at either the 120 or 180 code rate, the operation of the apparatus is the same except for the rate of the operation of the code following relay MS and the selection of the control relays A, R and L, relay RS being picked up in response to each code rate. When the code rate is 120 then control relay RA is picked up and relay A is released so that lamp 32 is illuminated to display an approach-medium indication and relay A is picked up in response to the 180 code rate so that lamp 29 of signal CS is illuminated to display a clear signal indication.

Referring again to Fig. 3, if the load or impedance in the plate circuit is that represented by the load line V—W and if an alternating voltage is applied to control grid 10 of the electron tube TT which drives the grid to a negative voltage of two volts (e. g. = -2) the average value of the direct current in the plate circuit is reduced from a value indicated by the line PA to a value indicated by the line PB. The line V—W represents the conventional load line for amplifiers of the type here involved. I have found that if instead of a plate circuit load represented by the line V—W the load is increased to a value represented by the line X—Y of Fig. 3, the change in the average value of the direct current plate circuit will be increased when the same applied grid voltage is applied to control grid 10 and would be reduced to a value represented by the line PC of Fig. 3. This increase in the change of the average value of the plate current is due to the presence of high impedance provided by the transformers T2 and T3. In other words, the reactor transformer T2 which is of high impedance to the alternating component of a plate circuit current and the low frequency transformer T2 and condenser 17 which are of low impedance to the high frequency variation of the plate circuit current are effective to increase the change in the average value of the plate circuit current in response to a given grid voltage.

In Fig. 2, the apparatus is the same as in Fig. 1, except a code following relay MS1 replaces the code following relay MS, the winding 38 of relay

MS1 being interposed in the plate circuit of tube TT and transformer T3 being omitted. Condenser 17 is connected across winding 38 of relay MS1 to by-pass the alternating current component of the plate circuit current around relay MS1. Relay MS1 is operated in response to the variation of the average value of the plate circuit current for tube TT, being picked up to close front contact 39 when no voltage is applied to control grid 10 and being released to close back contact 40 when the average value of the plate current is reduced due to the grid voltage applied to grid 10 during each on period of the coded current. Hence code following relay MS1 is operated at a rate corresponding to the code rate of the track rail current the same as code following relay MS of Fig. 1. Slow release relay RS of Fig. 2 is controlled by energy transferred through transformer T2 the same as in Fig. 1 and hence operation of code following relay MS1 in response to coded alternating track rail current causes direct current to be alternately supplied to the two portions of primary winding 22 of decoding transformer DT and an electromotive force of a corresponding frequency is induced in secondary winding 23 of the decoding transformer and applied to the decoding means DM to govern the control relays A, R and L. It is to be seen, therefore, that the apparatus of Fig. 2 operates in substantially the same manner as the apparatus of Fig. 1 in response to coded alternating rail current.

It is to be seen therefore that I have provided novel and improved amplifiers for railway traffic controlling apparatus which are operable when connected to a single 32 volt source of direct current. Transformers T2 and T3 provide a plate circuit for the electron tube which provides an increase in the change of the average value of the direct current due to a given applied grid voltage and effective operation of the code following relay is assured. Also the slow release relay RS is effective to check the presence of the alternating current component of the plate circuit and a cab signal indication due to an intermittent open circuit condition is avoided.

It should be pointed out that the principle set forth herein lends itself very effectively to control circuits in which a considerable change in direct current is required by the application of a relatively small alternating voltage.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. In railway traffic controlling apparatus for use with a receiving circuit mounted on a train in inductive relation to the track rails for receiving an electromotive force when alternating current coded at a given rate is supplied to the rails, the combination comprising: an electron tube having a plate, a cathode and a control grid mounted on the train; a grid circuit connected across said grid and cathode of the tube and coupled to said receiving circuit to apply to the grid the electromotive force received by said receiving circuit, a control winding, a condenser, a transformer; a plate circuit including a current source, the primary winding of said transformer

and said control winding and said condenser in multiple and connected across said plate and cathode of the tube; contact means controlled by said control winding in response to the variations of the plate circuit current caused by the on and off code periods of such electromotive force applied to said grid, a relay connected to the secondary winding of said transformer to control that relay in response to the alternating current component of the plate circuit current caused by said electromotive force applied to said grid, and a train carried signaling circuit controlled jointly by said relay and said contact means.

2. In railway traffic controlling apparatus for use with a receiving circuit mounted on a train in inductive relation to the track rails for receiving an electromotive force when alternating current coded at a given rate is supplied to the rails, the combination comprising: an electron tube having a plate, a cathode and a control grid mounted on the train; a grid circuit connected across said grid and cathode of the tube and coupled to said receiving circuit to apply to the grid the electromotive force received by said receiving circuit, a transformer: a plate circuit including a current source, the primary winding of said transformer and another winding and connected across said plate and cathode of the tube; a contact member controlled by said other winding and operable to engage a first and a second contact in response to the changes in the energization of said other winding due to the variations in the plate circuit current caused by the on and off code periods of said electromotive force applied to said grid, a slow release relay connected to the secondary winding of said transformer through a rectifier to pick up that relay in response to the alternating current component of the plate circuit current caused by said electromotive force applied to said grid, and train carried signaling means controlled over a circuit including a front contact of said relay and said first and second contacts of said contact member.

3. In railway traffic controlling apparatus for use with a receiving circuit mounted on a train in inductive relation to the track rails for receiving an electromotive force when alternating current coded at a given rate is supplied to the rails, the combination comprising, an electron tube having a plate, a cathode and a control grid mounted on the train; a grid circuit connected across said grid and cathode of the tube and coupled to said receiving circuit to apply to the grid the electromotive force received by said receiving circuit, a transformer: a plate circuit including a current source and a winding of said transformer and connected across the plate and cathode of said tube, a code following relay electrically associated with said plate circuit to operate such relay in response to the variations of the plate circuit current caused by the on and off code periods of said electromotive force applied to said control grid, a slow release relay connected to another winding of said transformer through a rectifier to effectively energize said slow release relay in response to the alternating current component of the plate circuit current caused during each on period of said electromotive force applied to said control grid, and train carried signaling means controlled jointly by said code following relay and said slow release relay.

4. In railway traffic controlling apparatus for use with a receiving circuit mounted on a train in inductive relation to the track rails for receiv-

ing an electromotive force when alternating current coded at a given rate is supplied to the rails, the combination comprising: an electron tube having a plate, a cathode and a control grid mounted on the train; a grid circuit connected across said grid and cathode of the tube and coupled to said receiving circuit to apply to the grid the electromotive force received by said receiving circuit, a transformer: a plate circuit including a current source and a winding of said transformer and connected across the plate and cathode of said tube, a code following relay electrically associated with said plate circuit to operate such relay in response to the variations of the plate circuit current caused by the on and off code periods of said electromotive force applied to said control grid, a slow release relay connected to another winding of said transformer through a rectifier to effectively energize said slow release relay in response to the alternating current component of the plate circuit current caused by each on period of said electromotive force applied to said control grid, and train carried signaling means controlled by said relays and effectively energized when and only when said slow release relay is picked up and said code following relay is operated.

5. In railway traffic controlling apparatus for use with a receiving circuit coupled to a transmitting circuit for receiving an electromotive force when alternating current coded at a given rate is supplied to such transmitting circuit, the combination comprising: an electron tube having a plate, a cathode and a control grid; a grid circuit connected across said grid and cathode of the tube and coupled to said receiving circuit to apply to the grid the electromotive force received by said receiving circuit, a plate circuit for said tube including a source of current, a code following relay electrically coupled to said plate circuit and operated by the increase and decrease of the direct current component of the plate circuit current due to the variations of the grid voltage caused by the on and off code periods of said electromotive force, a transformer having a first winding interposed in said plate circuit, another relay connected to a second winding of said transformer and effectively energized by the energy transferred thereto in response to the alternating current component of the plate circuit current caused by the harmonic variations of the grid voltage during each on period of said electromotive force, and a control circuit controlled jointly by said code following relay and said other relay.

6. In railway traffic controlling apparatus for use with a receiving circuit mounted on a train in inductive relation to the track rails for receiving an electromotive force when alternating current coded at a given code rate is supplied to the rails, the combination comprising: an electron tube having a plate, a cathode and a control grid mounted on the train; a grid circuit connected across said grid and cathode of the tube and coupled to said receiving circuit to apply to the grid the electromotive force received by said receiving circuit, a first and a second transformer: a plate circuit including a current source and a first winding of each of said transformers and connected across the plate and cathode of said tube, a code following relay coupled to a second winding of said first transformer for operation of the relay by the energy transferred thereto due to the decrease and increase in the average value of the plate circuit current caused by the electromotive force applied

to said grid, a slow release relay coupled to a second winding of said transformer for picking up that relay by the energy transferred thereto due to the alternating current component of the plate circuit current caused by said electromotive force applied to said grid, and train carried signaling means controlled by said relays effectively energized only when said code following relay is operated and said slow release relay is picked up.

7. In railway traffic controlling apparatus for use with a receiving circuit mounted on a train in inductive relation to the track rails for receiving an electromotive force when alternating current coded at a given rate is supplied to the rails, the combination comprising: an electron tube having a plate, a cathode and a control grid mounted on the train; a grid circuit connected across said grid and cathode of the tube and coupled to said receiving circuit to apply to the grid the electromotive force received by said receiving circuit, a first and a second transformer; a plate circuit including a current source and a first winding of each of said transformers and connected across the plate and cathode of said tube, a code following relay coupled to a second winding of said first transformer for operation of the relay by the energy transferred thereto due to the decrease and increase in the average value of the plate circuit current caused by the electromotive force applied to said grid, a slow release relay coupled to a second winding of said second transformer for picking up that relay by the energy transferred thereto due to the alternating current component of the plate circuit current caused by said electromotive force applied to said grid, decoding means responsive to current of a frequency corresponding to said given code rate, and a control circuit including a contact of said code following relay and a front contact of said slow release relay for supplying current to said decoding means.

8. In railway traffic controlling apparatus for use with a receiving circuit mounted on a train in inductive relation to the track rails for receiving an electromotive force when alternating current coded at a given rate is supplied to the rails, the combination comprising: an electron tube having a plate, a cathode and a control grid mounted on the train; a grid circuit connected across said grid and cathode of the tube and coupled to said receiving circuit to apply to the grid the electromotive force received by said receiving circuit, a transformer, a code following relay, a condenser; a plate circuit including a current source, a first winding of said transformer and a winding of said code following relay and said condenser in multiple and connected across the plate and cathode of said tube; said condenser effective to by-pass around said relay winding the alternating current component of the plate circuit current and ineffective to by-pass the low frequency variations of the plate circuit current as caused by said electromotive force applied to said control grid for operation of said relay in response to the on and off code periods of said electromotive force, a slow release relay connected to a second winding of said transformer through a rectifier to ener-

gize and pick up such relay in response to said alternating current component of the plate circuit current, decoding means responsive to current of a frequency corresponding to said given code rate, and means including a front contact of said slow release relay and a contact of said code following relay for supplying current to said decoding means.

9. In railway traffic controlling apparatus for use with a receiving circuit mounted on a train in inductive relation to the track rails for receiving an electromotive force when alternating current coded at a given rate is supplied to the rails, the combination comprising: an electron tube having a plate, a cathode and a control grid mounted on the train; a grid circuit connected across said grid and cathode of the tube and coupled to said receiving circuit to apply to the grid the electromotive force received by said receiving circuit, a current source, a heater circuit for said tube connected across said current source, a reactance device, a condenser, a winding; a circuit including said current source, said reactance device and said winding and condenser in multiple and connected across the plate and cathode of said tube to provide a plate circuit of relatively high impedance to current of said given frequency and of relatively high impedance to variations of the plate circuit current corresponding to said code rate; contact means controlled by said winding effectively operated to a first and a second position by the variations of the plate circuit current caused by the on and off periods of said electromotive force applied to said grid, and a train carried signaling circuit controlled by said contact means effectively energized only when said contact means is operated.

10. In railway traffic controlling apparatus for use with a receiving circuit mounted on a train in inductive relation to the track rails for receiving an electromotive force of a predetermined frequency and a preselected code rate when alternating current of said frequency and coded at said code rate is supplied to the rails, the combination comprising: a low voltage electron tube having a plate, a cathode and a control grid mounted on the train; a grid circuit including a winding coupled to said receiving circuit and a condenser and a resistor in multiple and connected across said grid and cathode of said tube, a low voltage source of direct current, a heater circuit for said tube connected across said current source, a reactance device of relatively high impedance at said predetermined frequency, another winding and another condenser connected in multiple; a plate circuit including said current source, said reactance device and said other winding and other condenser and connected across said plate and cathode of said tube, contact means controlled by said other winding effectively operated by the decrease and increase in the average value of the plate circuit current caused by the coded electromotive force applied to said grid because of said high impedance of said reactance device, and signaling means controlled by said contact means when operated.

RALPH K. CROOKS.

CERTIFICATE OF CORRECTION.

Patent No. 2,279,971.

April 14, 1942.

RALPH K. CROOKS.

It is hereby certified that error appears in the printed specification of the above numbered patent requiring correction as follows: Page 6, first column, line 2, claim 6, before "transformer" insert --second--; and that the said Letters Patent should be read with this correction therein that the same may conform to the record of the case in the Patent Office.

Signed and sealed this 26th day of May, A. D. 1942.

Henry Van Arsdale,
Acting Commissioner of Patents.

(Seal)
